UNITED STATES PATENT OFFICE

112,808

DESIGN FOR AN ASHTRAY OR SIMILAR ARTICLE

Gregory S. Dolgorukov, Detroit, Mich.

Application December 24, 1937, Serial No. 73,851

Term of patent 14 years

To all whom it may concern:

Be it known that I, Gregory S. Dolgorukov, a citizen of the United States, residing at Detroit, county of Wayne, State of Michigan, have invented a new, original, and ornamental Design for an Ash Tray or Similar Article.

The present application is a continuation in part of my co-pending application Serial No. D-62,672, filed May 16, 1936.

The following is the specification of an ash tray embodying my new design, reference being had in said specification to the accompanying drawing, forming a part thereof, in which drawing

Fig. 1 is an exploded view of an ash tray embodying my new design, the glass inlay being removed from the body of the ash tray.

Fig. 2 is a perspective view of the assembled ash tray, showing my new design.

The design consists of a relatively flat body of prismatic configuration of substantially the outline shown having a central depression forming a chamber for an ash receptacle, the chamber being open at its top and surrounded by an up-standing ledge providing a shouldered top surface formed with spaced substantially radial grooves in its top, and a receptacle in said chamber having circumferential stripes or bands on its wall of a color contrasting with the body.

I claim:

The ornamental design for an ash tray or similar article, substantially as shown and described.

GREGORY S. DOLGORUKOV.
